UNITED STATES PATENT OFFICE.

ROBERT E. CONLIN, OF POUGHKEEPSIE, NEW YORK.

DESIGN FOR A HAIR-CRIMPER MEMBER.

SPECIFICATION forming part of Design No. 28,796, dated June 7, 1898.

Application filed August 31, 1896. Serial No. 604,499. Term of patent 14 years.

To all whom it may concern:

Be it known that I, ROBERT E. CONLIN, a citizen of the United States, residing at Poughkeepsie, in the county of Dutchess and State 5 of New York, have invented a new and original Design for a Hair-Crimper Member, of which the following is a specification.

This invention relates to a new and original 10 design for a hair-crimper member; and it has for its object to provide a design of this character which shall be both useful and ornamental.

The leading feature of the design resides 15 in a pronged jaw having extended from its end, opposite the prongs, a rounded handle-shank provided between its ends with a laterally-bowed U-shaped bend and at one end with a cylindrical hand-grasp.

In the drawings, Figure 1 is a perspective 20 view of a hair-crimper member embodying the herein-described design, and Fig. 2 is a side elevation thereof.

Referring to the accompanying drawings,

the numeral 1 designates a hair-crimper jaw having an approximately rectangular central 25 portion 2 and provided at one end with a plurality of straight parallel cylindrical prongs 3. At the end opposite the plurality of prongs 3 the jaw 1 has extended therefrom a rounded handle-shank 4, which handle-shank is provided between its ends with a laterally-bowed U-shaped bend 5 and at one side of said bend with a cylindrical hand-grasp 6, which completes the design of the crimper member. 30

What I claim is—

The design for a hair-crimper member, herein shown and described.

In testimony that I claim the foregoing as my own I have hereto affixed my signature in 40 the presence of two witnesses.

ROBERT E. CONLIN.
